(57) CLAIM

The ornamental design for a soft sculpture, as shown and described.

DESCRIPTION

FIG. 1 is a front view of a soft sculpture showing our ornamental design;

FIG. 2 is a back view thereof;

FIG. 3 is a right-side view thereof;

FIG. 4 is a left-side view thereof;

FIG. 5 is a bottom view thereof; and,

FIG. 6 is a top view thereof.

The broken lines depict portions of the soft sculpture that form no part of the claimed design.
